UNITED STATES PATENT OFFICE.

BERNARD A. NARVESON, OF GRAND RAPIDS, MINNESOTA, ASSIGNEE OF ONE-HALF TO
OSCAR T. ANDERSON, OF GRAND RAPIDS, MINNESOTA.

SPARK-PLUG TESTER.

1,264,872.

Specification of Letters Patent. Patented Apr. 30, 1918.

Application filed December 26, 1916. Serial No. 138,919.

To all whom it may concern:

Be it known that I, BERNARD A. NARVESON, a citizen of the United States, residing at Grand Rapids, in the county of Itasca, 5 State of Minnesota, have invented certain new and useful Improvements in Spark-Plug Testers; and I do hereby declare the following to be a full, clear, and exact description of the invention, such as will enable others skilled in the art to which it appertains to make and use the same.

This invention relates to ignition systems for automobiles, and particularly to spark testing apparatuses for use in connection 15 with the systems.

The object of this invention is to provide a testing apparatus for use in ignition systems of internal combustion engines by means of which faulty plugs may be instantaneously detected. In this connection, I insert between the engine or ground and the spark plugs, a testing device which provides a series of gaps corresponding to the number of plugs, and in which the corresponding terminals upon one side of the gaps are formed from a single contact plate from which the ground wire extends to the engine. By this arrangement ground electrodes of the plugs are not grounded in the shells of the spark plug as is customary, but they are insulated from the shells, and consequently the engine casing, and are connected to the testing device which in turn is grounded upon the engine.

35 A further object of this invention is to provide a circuit closing device for use in connection with the tester by means of which the latter may be eliminated as a tester under ordinary running conditions.

40 With the above objects in view and such others as will hereinafter appear, my invention will now be fully set forth and described, reference being had to the accompanying drawings.

45 In the drawings:—

Figure 1 is a front elevation of the tester, Fig. 2 is a section on line 2—2 of Fig. 1.

Fig. 3 is a vertical section through one form of the spark plug used in the system, 50 and

Fig. 4 is a diagrammatic showing of the system including my tester.

Referring more particularly to the drawings, 1 represents a housing or casing of 55 any suitable material which consists of a

back plate 2 and an overhanging top portion and a depending flange 3. Secured to the back 2 is a base 4 of hard rubber or other suitable insulating material in which a number of contact heads 5 are mounted, 60 said heads 5 preferably being conical in form and terminating in the threaded stems 6 which pass through the base 4 and are provided at their lower ends with the binding nuts 7. Threaded into the rear edge of the 65 base 4 is a plurality of set screws 8 which pass through vertical slots 9 in the back plate 2 whereby the base 4 may be vertically adjusted in order to properly set the points of the contact heads 5 in forming the testing 70 gaps. Secured to the top or cover plate 1 is a conductor plate 10 which carries the depending web 11 and the spaced wall 12, the web 11 and the wall 12 providing a longitudinal passage-way or slot 13 in which 75 the sliding contact plate 14 is seated.

The web 11 extends throughout the length of the casing, and is formed along its lower edge into a plurality of spark points or terminals 15 which are spaced from the 80 points of the contact heads 5, so that a series of spark gaps are thereby provided. A terminal 16 connected to the plate 10 provides a means for continuing a ground wire to the engine or other ground. The slide 85 plate 14 is held in elevated position in its slideway 13 by means of the manipulating device 17 entered through the casing and, supporting the plate 14, is directed to control the latter so that it may be carried into 90 contact with all of the heads 5 when the device is not in use as a tester, so that the flow of current may not be interrupted by the gaps of the tester when it is not necessary.

The front of the casing 1 is closed by means of a glass plate 18 which rests in a groove in the base 4 and has its upper edge engaged between the flange 3 and the forward edge of the plate 10.

In interposing the tester between the spark plugs and the ground, it becomes necessary to alter the spark plug structure by eliminating the ground terminals and carrying both of the spark terminals to binding 105 posts upon the outer end of the plug. Thus, in one instance, the plugs shown in Fig. 3 may be employed. The usual metal shell 20 is threaded into the cylinder head and has the annular recess 21 in which the por-

95

100

105

110

celain 22 is inserted upon the insulating washer 23. The lower end of the shell is annularly bored to carry the expansion joint 24 and the porcelain 25 which in turn, is 5 provided with the parallel passages 26. Extending through the passages 26 and the porcelain 22 are the electrodes 27 and 28, the upper or outer ends of the electrodes 27 and 28 being carried to the binding posts 10 29 and 30 respectively. Thus, one binding post will be connected to the coil box and the other binding post will be connected to a corresponding contact head 5 in the tester 15 casing, and the current thence passes to the ground through the web 11.

The diagram of Fig. 4 shows the method of connecting the plug and tester in the ignition circuit. Only one of the plugs is shown in the circuit, as an explanation of 20 this circuit will obviously explain all of the plug circuits. A wire 31 from the coil box, magnetic or other current source (not shown) is connected to the binding post 29. The current passes thence through the electrode 27, thence to the electrode 28 and passes then to the binding post 30, and by 25 means of the wire 32 is connected to the binding screws 7 to the electrodes or contacts 5. The current jumps the gap between the electrodes 5 and the corresponding 30 points 15 of the web 11 and then by means of the wire 33 is grounded in an obvious manner.

The adjustment of the gaps between the 35 electrodes 5 and the points 15 is obvious through the manipulation of the set screws 8, and it is also obvious that when it is desired to eliminate the gap of the testing device so that the flow of the current is un-

interrupted, the plate 13 is lowered so that 40 it spans all of the contacts or electrodes 5, and the testing device becomes essentially a grounding device.

What I claim as my invention is:—

1. A testing device for ignition systems, 45 comprising a casing, a plurality of insulated electrodes in the casing, a continuous plate mounted in the casing and having a corresponding plurality of points forming spark gaps with the electrodes and a plate for 50 spanning the gaps to simultaneously eliminate them.

2. A testing device for ignition systems comprising a casing, a plurality of insulated electrodes in the casing, and a continuous 55 plate mounted in the casing and having a corresponding plurality of points forming spark gaps with the electrodes, a common means for adjusting the gaps and means for instantaneously spanning all of the gaps to 60 eliminate them.

3. A testing device for ignition systems comprising a casing, a plurality of insulated electrodes in the casing, a continuous plate mounted in the casing, and having a corresponding plurality of points forming spark gaps with the electrodes, a common means for closing the gaps, and a slide plate associated with the continuous plate and adapted to be moved into contact with all of the 70 electrodes to close all of the gaps.

In testimony whereof, I affix my signature, in the presence of two witnesses.

BERNARD A. NARVESON.
